UNITED STATES PATENT OFFICE.

GEORGE MORRISON, OF LOCKPORT, ILLINOIS.

IMPROVED PLATE FOR ARTIFICIAL TEETH.

Specification forming part of Letters Patent No. 88,798, dated April 13, 1869.

To all whom it may concern:

Be it known that I, GEORGE MORRISON, of Lockport, in Will county and State of Illinois, have invented a new and useful Improvement in Plates for Artificial Teeth; and that the following is a full, clear, and exact description of the same, reference being had to the annexed drawings, making a part of this specification, in which—

Figure 1 is a plan view on the top, and Fig. 2 a cross-sectional view of the same on the line *x*.

One of the greatest difficulties and annoyances experienced by persons obliged to wear artificial teeth (especially the upper set) is that the plates are continually dropping out on account of the air from without finding ingress into the air-chamber usually made in the roof of the plate. This air-chamber is the best means employed to hold suction-plates up into their place, by means of exhausting the air therefrom, which causes a vacuum between the roof of the mouth and the plate, so that the pressure of the air on the plate holds it firm in place; but, however, it is well known that to allow the least quantity of air from without into the air-chamber will immediately cause it to relax its pressure to the roof of the mouth, and will finally drop entirely down and fall out.

My invention consists in a device expressly for the purpose of obviating this difficulty, by so constructing the air-chamber *c* that the air cannot so easily find ingress, which I do by constructing a flange or annular elevated projection (shown at *a*, Figs. 1 and 2) around the

edge of the air-chamber, which serves as a wall around the same and a barrier to the air from without. This projection easily embeds itself into the fleshy part of the roof of the mouth, and is not painful or difficult to wear.

It will be readily seen that the projection or wall must be of great service in preventing the ingress of air into the chamber by compelling it to pass over it, which would be difficult on account of its being embedded into the roof of the mouth. This projection may be used on any kind of plate, whether vulcanite or metal, and on any part thereof that it may be necessary to be used.

It will also be seen that if the plate should not exactly fit the roof of the mouth the flange will prevent the air from finding ingress just as well, and it would be no more liable to fall out than if the fit were good.

Claims.

Having thus described my invention, what I claim as new, and desire to secure by Letters Patent, is—

1. The annular projection or wall *a*, surrounding the air-chamber *c*, constructed and arranged as and for the purposes set forth.
2. Preventing the air from without from entering the air-chamber *c* by means of an elevated projection or wall surrounding the same, substantially as described.

GEO. MORRISON.
